US0D1044416S

(12) **United States Design Patent** (10) **Patent No.:** **US D1,044,416 S**
(45) **Date of Patent:** **** Oct. 1, 2024**

(54) **INSULATING DEVICE**

(71) Applicant: **YETI Coolers, LLC**, Austin, TX (US)

(72) Inventors: **Roy Joseph Seiders**, Austin, TX (US);
Christopher M. Keller, Austin, TX (US)

(73) Assignee: **YETI Coolers, LLC**, Austin, TX (US)

(**) Term: **15 Years**

(21) Appl. No.: **29/731,183**

(22) Filed: **Apr. 13, 2020**

Related U.S. Application Data

(63) Continuation of application No. 29/661,068, filed on Aug. 24, 2018, now Pat. No. Des. 880,862, which is a continuation of application No. 29/617,966, filed on Sep. 18, 2017, now Pat. No. Des. 882,956, which is a continuation of application No. 29/544,617, filed on Nov. 4, 2015, now Pat. No. Des. 797,454, which is a continuation of application No. 29/503,060, filed on Sep. 23, 2014, now Pat. No. Des. 787,187.

(57) **CLAIM**

The ornamental design for an insulating device, as shown and described.

DESCRIPTION

FIG. 1 is a top, front, left perspective view of an insulating device showing our new design;

FIG. 2 is a front view thereof;

FIG. 3 is a rear view thereof;

FIG. 4 is a bottom view thereof;

FIG. 5 is a left side view thereof; and,

FIG. 6 is a right side view thereof.

The broken lines illustrate portions of the article that form no part of the claimed design.

1 Claim, 6 Drawing Sheets
